UNITED STATES PATENT OFFICE.

NEAL TRIMBLE MCKEE, OF DOBBS FERRY, NEW YORK, ASSIGNOR TO LOCOMOTIVE SUPERHEATER COMPANY, OF NEW YORK, N. Y., A CORPORATION OF DELAWARE.

GRIPPING AND FORGING DIE.

1,151,601.

Specification of Letters Patent. Patented Aug. 31, 1915.

Application filed July 7, 1914. Serial No. 849,433.

To all whom it may concern:

Be it known that I, NEAL TRIMBLE MCKEE, a citizen of the United States, residing at Dobbs Ferry, in the county of Westchester, 5 State of New York, have invented a certain new and useful Improvement in Gripping and Forging Dies, of which the following is a specification.

My invention relates to an improved gripping and forging die and has for its object to provide a die which shall grip the work to be forged or otherwise treated with a pressure which will increase as the operating pressure which tends to force the work out 15 of the die increases.

More particularly my invention relates to a die of the class described in which the gripping pressure increases automatically as the operating pressure is increased.

20 I find my improved gripping and forging die especially useful in the manufacture of welded pipe bends for connecting the two straight legs of a superheater element but do not limit its use to this work as its principle is widely applicable to dies for various purposes.

In an application for patent filed by Charles H. True and myself on April 30, 1914 and entitled "Pipe bends," we showed 30 and described a set of dies for making superheater pipe bends, said dies comprising a two part female die and a male breeches die. In using said dies, as explained in said application, two pipe lengths to be joined by a pipe bend were, while at welding heat, clamped between the two halves of the female die, and the breeches die then forcibly inserted into the two pipe ends so as to cut through adjacent walls, and then abut said 40 cut portions and weld them together. In using the said dies of the application mentioned, the pressure applied to the breeches die to perform its necessary function is so great that the pipe lengths are apt to slip in the female die so that back stops, abutting 45 against the remote ends of the two pipe lengths, or some equivalent holding means, becomes necessary. In my improved die herewith disclosed I am able to hold the pipe lengths by means of the female die alone 50 without the aid of any external device such as back stops and the like.

My invention will be better understood by referring to the accompanying drawings in which—

55 Figure 1 represents a plan view, partly in section, showing my improved die together with certain associated parts necessary in the production of a pipe bend according to the disclosure of the above mentioned application, Serial No. 835,360, said die and parts being represented as attached to and operated by a suitable machine of known type; Fig. 2 is a view, similar to Fig. 1, showing a later position of the die and parts; Fig. 3 is 60 a section along the line 3—3 of Fig. 2; Fig. 4 is a view, similar to Figs. 1 and 2, showing a still later position of the parts; Fig. 5 is a section along the line 5—5 of Fig. 4; Fig. 6 is an end elevation, taken from the right of 65 Fig. 4; and Fig. 7 is a perspective view of the incomplete pipe bend after it is taken from the die and before the latter operations necessary to complete it have been performed.

70 In the drawings, 1 and 2 represent a pair of fixed bed members integrally or otherwise attached to the main frame of a suitable machine and having an open space or throat between them. To one of these members is 75 fixed a half, 3, of the female forming die, the other half, 4, of said forming die being arranged to slide in a guide-way 5, formed in the other member 2, by means of a link 6 pivotally attached to the die and operatively 80 connected with suitable toggle driving mechanism (not shown). The opposed faces of the die halves 3 and 4 are grooved and shaped as shown in Figs. 1 and 4 of the application No. 835,360 above referred to so 85 as to hold the two pipe lengths which are to be united by a return bend and to coöperate with the breeches die of said application in the production of said bend. When the two halves 3 and 4 are brought together with 90 pipe lengths in place said pipe lengths will lie in a single vertical plane as shown in the several figures.

95 A holder 7 operatively connected with the machine so as to reciprocate to and fro, as 100 shown by the arrow, holds the breeches die 8 in position so that, when the pipe lengths are clamped in the female die, the legs of the breeches die will enter the ends of said pipe.

lengths, cut and abut the cut portions of adjacent walls thereof, and then weld said walls together to produce the incomplete bend, shown in Fig. 7, as explained in the specification No. 835,360 aforesaid.

A rectangular sectioned gripping block or member 9 fits into a similar but larger recess formed in one end of the die half 3; this recess includes end portions of the two 10 grooves previously referred to, for the respective pipe lengths. This block is grooved to correspond with the grooves of the die. A stout pivot 10 is fitted into the die half 3 and a pressure block 11, of rectangular section, having opposite grooved faces one of 15 which engages the periphery of pivot 10 and the other of which engages a convex rib 12 formed on the inner side of block 9, is slidably fitted in a recess or guide-way 13 20 which opens into the recess of block 9.

A spindle 14, having its inner end fixed in block 9, lies in an enlarged hole pierced through the die block 3 and has its outer end, lying outside of the die block, flat and 25 slotted as at 15. Adjacent to the spindle 14, a bracket 16 is fixed to the end of the die block and carries a pivotally attached bell crank lever 17, one arm of which has a cam pin 18 adapted to engage a diamond shaped 30 cam member 19 depending from a bracket 20 attached to and moving with the holder 7. The other arm 20' of lever 17 is connected by means of a spring 21 to the fixed member 2.

35 The other end of block 9 is connected by a tension spring 22 to the frame of the machine as shown so as to be subject to a constant pull in the direction indicated by the arrow at the side of said spring.

40 The bell crank lever 17 has a third arm 22' which carries a pin 23 in engagement with the slot 15.

The operation of my invention is as follows: The parts being as shown in Fig. 1, 45 the two pipe lengths 24 and 25 are placed in the grooves of the die half 3 and the machine started thus causing die half 4 to be slid in its guide-way 5 by the link 6, in the direction of the arrow, until the two die halves come together and clamp the pipe lengths. In this position the link 6, which 50 is one member of a toggle joint in the machine chosen, lies substantially at right angles to the length of the die and the toggle 55 is fully extended so that any force tending to separate the die halves manifests itself as a compression strain in the length of the link which is resisted by the fixed support upon the frame of the machine of the other end 60 of the toggle. As the die half 4 is advanced toward die 3 the holder 7 moves in the direction of the arrow so that when the two die halves finally come together the breeches die will be just about to enter the pipe ends

(see Fig. 2). As the breeches die begins to 65 advance from the position shown in Fig. 1 to that shown in Fig. 2, the cam pin 18 engages the upper surface of cam member 19 so as to act upon bell crank lever 17 and draw the block 9 to its left hand limit thereby, owing to the larger recess in which block 9 fits, carrying the grooves of the block somewhat away from the pipe lengths as they are clamped in the female die. As the breeches die continues to advance from the position shown in Fig. 2 so that its legs enter the pipe ends the cam pin 18 will slip over the left hand end of cam member 19 and permit the arms 20' and 22' of the bell crank lever to be pulled back again by the 70 spring 21 parallel with the ends of the die 3, 4, thus jamming the grooves of block 9 down against the two pipe lengths. As the legs of the breeches die continue on into the pipe ends so as to cut the adjacent walls and 75 abut and weld said walls together, as described in the previously referred to application No. 835,360, the end pressure thus brought to bear upon the pipes will, by reason of the frictional engagement between 80 block 9 and the pipe lengths, tend to move block 9 to the right. Owing to the presence of pivot 10 and pressure block 11, however, the effect of this tendency will be to wedge 85 block 9 against the pipe lengths with a pressure which will increase with the end pressure due to the breeches die. The pipe lengths will, therefore, be securely held, 90 without slip, despite the great pressure brought to bear upon their ends. Owing to 95 the length of block 9 the pipe lengths are firmly and securely held without crushing. The breeches die having reached the limit of its movement and the pipe lengths being 100 welded together is withdrawn by the holder 7 in the normal operation of the machine. 105 As the holder is thus withdrawn, the cam pin 18, which is now held in its lowermost position by the tension of the spring 21, strikes the lower contour line of cam member 19, slides over the same and frees itself as the holder reaches its limiting position to the left so as to be in position to again draw 110 block 9 to the left as another pair of pipe lengths is clamped in the die. As the 115 breeches die is withdrawn the die half 4 is slid downwardly thus releasing the partially completed pipe bend which now has the form shown in Fig. 7.

While I have shown a preferred form of 120 my improved gripping and forging die, as used for a preferred purpose, many changes of detail may be made within the spirit of the invention and scope of the claims which follow, since the principle employed is one 125 which may be adapted to forging, pressing, cutting operations and the like which are quite different from one another but which

have the common characteristic that the manipulative force tends to push the work from the die.

I therefore claim:

- 5 1. A die comprising, in combination, a plurality of die members adapted to be fixedly closed together so as to grip the work, means for producing endwise operative pressure upon the work, and means 10 controlled by the endwise pressure for increasing the gripping pressure after the dies have been closed.

- 15 2. A die comprising, in combination, a plurality of die members adapted to be fixedly closed together so as to grip the work, means for producing endwise operative pressure upon the work, and means controlled by the endwise pressure for increasing the gripping pressure as the operative 20 pressure is increased.

- 25 3. A die comprising, in combination, a plurality of die members adapted to be fixedly closed together so as to grip the work, means for producing endwise operative pressure upon the work, and means for automatically increasing the gripping pressure as the operative pressure is increased.

- 30 4. A die comprising, in combination, a plurality of die members adapted to be fixedly closed together so as to grip the work, means for producing endwise operative pressure upon the work, and means for automatically increasing the gripping pressure as the operative pressure is increased and proportionately thereto.

- 35 5. A die comprising, in combination, a plurality of die members adapted to be fixedly clamped together so as to hold the work, means for producing endwise operative pressure upon the work and a secondary gripping member arranged to co-act with one of said members so as to apply an increased pressure to the work as the operative pressure is increased.

- 45 6. A die comprising, in combination, a plurality of die members adapted to be fixedly clamped together so as to hold the work, means for producing endwise operative pressure upon the work and a secondary gripping member between the work and one of said members, said secondary member being arranged to put an increased pressure upon the work as the operative pressure is increased.

- 55 7. A die comprising, in combination, a

plurality of die members adapted to be fixedly clamped together so as to hold the work, means for producing endwise operative pressure upon the work, a secondary gripping member between the work and one of said members, means for holding said secondary member out of gripping contact with the work until the same is gripped by the die members, and means for contacting the secondary member with the work 60 when the operative pressure goes on whereby the gripping pressure increases with the operating pressure.

8. In combination, a pair of relatively movable die members adapted to clamp the work, an abutment, a movable gripping block recessed in one of said die members between said abutment and the work, a male die member, and means controlled by the male die member for holding the 70 gripping block out of contact with the work until the operative pressure is applied and thus permitting said block to be wedged between the work and the abutment.

9. In combination, a pair of relatively movable die members adapted to clamp the work, an abutment fixedly attached to one of said die members, a movable gripping block recessed in the last named die member between said abutment and the work, 80 a male die member, and means controlled by the male die member for holding the gripping block out of contact with the work until the operative pressure is applied and thus permitting said block to be wedged 85 between the work and the abutment.

10. A die comprising, in combination, a plurality of die members adapted to be fixedly clamped together so as to hold the work, means for producing endwise operative pressure upon the work, a movable secondary wedging member recessed in the face of one of said die members adjacent to the work, and means for holding said secondary member out of wedging 95 contact with the work until the endwise pressure begins to act.

In testimony whereof, I have hereunto set my hand in the presence of two subscribing witnesses.

NEAL TRIMBLE McKEE.
